UNITED STATES PATENT OFFICE.

LEWIS R. BARBER, OF FRESNO, CALIFORNIA, ASSIGNOR TO LISENBY MANUFACTURING COMPANY, OF FRESNO, CALIFORNIA, A CORPORATION.

PAPER-FEED MECHANISM.

Application filed May 27, 1922. Serial No. 564,141.

To all whom it may concern:

Be it known that I, LEWIS R. BARBER, a citizen of the United States, residing at Fresno, county of Fresno, State of California, have 5 invented certain new and useful Improvements in Paper-Feed Mechanism; and I do declare the following to be a full, clear, and exact description of the same, reference being had to the accompanying drawings, and 10 to the characters of reference marked thereon, which form a part of this application.

This invention relates to improvements in printing presses, and particularly to the paper feed mechanism thereof, the type of 15 press in which this mechanism is incorporated being that shown in United States Patents No. 1016756, February 6th, 1912; and No. 1041314, October 15th, 1912, my feeding mechanism being incorporated with 20 the adjustable bail structure as shown in Patent No. 1,413,842, dated April 25th, 1922.

In this device, the paper is fed between the feed-rollers of the bail, one of which rollers is movable vertically with respect to 25 the other, and is then stopped from advancement by means of fingers which are raised out of the way when the rollers come together to feed the paper forward at a pre-determined period in the cycle of operation 30 of the press.

If these fingers are lifted too soon, the paper is apt to slide forward before it should, or become crooked; in either case destroying the register of the sheet of paper 35 with the matter to be printed thereon. Or the fingers may move out of the way too late, after the rollers have come together, thus causing the paper to be crumpled.

The principal object of my invention 40 therefore is to provide a means whereby the fingers will be released or raised from the paper at the precise instance necessary for perfect cooperation with the feed rollers.

Another object is to provide for adjustment of said means, so that the time of actuation of the fingers, and the extent of their movement, may be regulated to a nicety.

I have also provided a novel form of adjustable spring means for insuring rapid 50 and positive movement of the bail.

A further object of the invention is to produce a simple and inexpensive device, and yet one which will be exceedingly effective for the purposes for which it is designed.

These objects I accomplish by means of 55 such structure and relative arrangement of parts as will fully appear by a perusal of the following specification and claims.

In the drawings similar characters of reference indicate corresponding parts in the 60 several views.

Fig. 1 is a top plan view of the bail and feed mechanism, showing my improved finger-control means, and the spring bail-control means. 65

Fig. 2 is a cross section taken on the line 2—2 of Fig. 1, showing the fingers depressed or in their normal position.

Fig. 3 is a similar view of the bail detached, showing the fingers raised. 70

Referring now more particularly to the characters of reference on the drawings, the numeral 1 denotes the side frames of the press, on which are fixed the dolly-boxes 2 of the feeding mechanism, and between and 75 in which is journaled the printing cylinder 3, carrying a driving gear 4 on one end, meshing with a rack 5 on the moving bed of the press.

Forward of the cylinder 3, and on the side 80 thereof opposite the gear 4 is the bail post 6, carrying on its lower and forward end the bail-post feeler-roller 7. This bail post is adjustably connected to the horizontal bar 8 of the bail, in the manner shown in the 85 above mentioned Patent No. 1,413,842, the bail post and bail for the purpose of this case being considered as a single unit.

This structure is pivoted to and between the boxes 2 at the end nearest the cylinder 90 by bearing pins 9, the one on the side adjacent the gear 3 having a pinion 10 meshing therewith and with a gear 11 provided with the bail feed-rolls 12, which are spaced 95 apart, and which are journaled by means of a shaft 13 in the bail forward of the pins 9.

In vertical alinement with the rolls 12 are the lower paper-feed rolls 14, journaled in the posts 2 under the rolls 12, and normally spaced therefrom. 100

Above the lower rolls 14 is the paper feed-plate 15, said rolls projecting therethrough slightly.

To the rear of said rolls and therebetween the plate 15 is provided with slots 16 to receive the ends of stop-fingers 17 formed with a horizontal bar 18 pivotally mounted to and between the boxes 2 ahead of the 105

bail, spring means 19 being arranged with the bar 18 to normally cause the fingers to project through the slots. Movement of the fingers in this direction is stopped and 5 the extent of projection adjusted by means of an eccentric roller 20 journaled in one of the boxes 2 and bearing against the bar 18.

Projecting outwardly or forward from the bar 18 is a rigid plate 21 adapted to be 10 engaged by an arm or finger 22 mounted on the bail-bar 8 for limited rocking movement as shown at 23.

Vertical adjustment of this arm is had by 15 means of two screws 24 and 25 to the rear of the rocking connection 23, the screw 24 being threaded into the arm and bearing on the bar 8, while the screw 25 passes freely through the said arm and is threaded into the bar 8. By this means, the vertical 20 spacing of the outer end of the arm from the plate 21 may be adjusted to suit, while the normal setting of the fingers may be regulated by turning the roller 20.

The roller 7 normally rides on a track 26 25 on the moving-bed of the press, which at a certain point has a drop as at 27 to allow the roller 7 to drop.

Normally, when the roller 7 is raised, the 30 fingers 17 are projected into the slots 16 so as to form a stop for any paper fed onto the plate 15, while the feed rolls 12 and 14 are separated.

When the roller 7 reaches the drop in 35 the track, the bail moves down and forwardly about the pivotal pins 9, causing the rolls 12 and 14 to gradually approach each other. At the same time the arm 22 is approaching the plate 21, until just at 40 the time the feed rolls come together to frictionally engage and feed the paper therebetween, the arm 22 strikes and depresses the plate 21, causing the fingers 17 to be raised free of the slots 16 just in time 45 to allow the paper to be fed freely between the fingers and feed plate.

The bail is positively caused to be moved forward by means of a rod 28 slidably 50 mounted in a bearing 29, adjacent the bail 8, said bearing being formed with a block 30 fixed to one of the boxes 2. The rod 28, in reduced size, passes freely through an adjustment screw 31, threaded into a bearing 29^a on the block 30 opposite the bearing 29, while a helical spring 32 is about 55 the rod 28 between the adjacent end of the screw and the termination of the enlarged portion of the rod 28, both of which are between the bearings 29 and 29^a.

By means of this construction, the rod 60 is free to slide, and has a pair of spaced bearings, to give a substantial mounting, while at the same time the tension of the spring, and hence the pressure on the rod, may be adjusted at any time.

65 From the foregoing description it will be

readily seen that I have produced such a device as substantially fulfills the objects of the invention as set forth herein.

While this specification sets forth in detail the present and preferred construction 70 of the device, still in practice such deviations from such detail may be resorted to as do not form a departure from the spirit of the invention, as defined by the appended claims.

Having thus described my invention, what 75 I claim as new and useful and desire to secure by Letters Patent, is:

1. In a printing press, a pivoted bail, upper feed-rolls pivoted therein, lower feed rolls pivoted independently of the bail and 80 normally spaced from the upper rolls, a paper-feed plate fixed with respect to the lower rolls, a transverse bar structure pivoted independently of the bail, fingers mounted on the bar and normally projecting 85 below the surface of the plate, means for tilting the bail to cause the upper rolls to contact with the lower rolls, and a member mounted on the bail and adapted to engage the bar at a point thereon such that a depression of said bar at that point will cause 90 the fingers to be raised, said member being normally vertically spaced from the bar, and means for enabling said normal spacing of said member from the bar to be altered at 95 will.

2. In a printing press, a pivoted bail, upper feed-rolls pivoted therein, lower feed rolls pivoted independently of the bail, and 100 normally spaced from the upper rolls, a paper-feed plate cooperating with the lower rolls and fixed with respect thereto, fingers pivoted independently of the bail and normally projecting below the surface of the plate, means for tilting the bail about its 105 pivotal connections to cause the upper feed rolls to contact with the lower rolls, and means carried by the bail and acting on the fingers after the bail has started to tilt and to raise the same above the plate by the time 110 the rolls contact.

3. In a printing press, a pivoted bail, upper feed-rolls pivoted therein, lower feed rolls pivoted independently of the bail, and 115 normally spaced from the upper rolls, a paper-feed plate co-operating with the lower rolls and fixed with respect thereto, fingers pivoted independently of the bail and normally projecting below the surface of the plate, means for tilting the bail about its 120 pivotal connections to cause the upper feed rolls to contact with the lower rolls, means carried by the bail and movable therewith for raising the fingers above the feed plate, and means whereby such raising of the fingers may be adjustably timed with respect 125 to the contacting of the rolls.

4. In a printing press, a pivoted bail, a block having spaced bearings fixed with respect thereto, a screw threaded into the bear- 130

ing farthest from the bail, a rod slideable through the other bearing and through the screw and contacting with the bail, an enlarged portion on the rod and spring means between the inner end of the screw and the enlarged portion of the rod and forcing the rod into contact with the bail at all times, the screw being adjustable, whereby the tension of the spring and the resultant pressure of the rod against the bail may be varied at will.

5. In a printing press, a pivoted bail, a block fixed with respect to the bail and having spaced and alined bearings whose axis

are at right angles to but offset from the axis of the bail, a screw adjustably threaded into the bearing farthest from the bail, a rod slideable through the other bearing and through the screw whereby the entire length of the latter serves as a bearing for the rod, and enlarged portion on the rod, and spring means on the rod between the inner end of the screw and the enlarged portion of the rod and acting to hold the latter in contact with the bail.
